Patented Dec. 5, 1967

209,467

SHOWER CURTAIN HOOK

James A. King, Orleans, Mass., assignor to Ames Shower Curtain Co., Inc., New York, N.Y., a corporation of New York

Filed Apr. 27, 1967, Ser. No. 6,855

Term of patent 14 years

(Cl. 54—1)

FIG. 1

FIG. 2

FIG. 3

FIG. 4

FIG. 5

FIG. 1 is a side elevational view of a shower curtain hook embodying my new design, the opposite side being a mirror image thereof;

FIG. 2 is a right side elevational view thereof;

FIG. 3 is a left side elevational view thereof;

FIG. 4 is top plan view thereof; and

FIG. 5 is a bottom plan view thereof.

I claim:

The ornamental design for a shower curtain hook, as shown and described.
